(57) **CLAIM**

I claim the ornamental design for an outsole, as shown and described.

DESCRIPTION

FIG. 1 is a bottom plan view of an outsole showing my new design;

FIG. 2 is a left side elevational view thereof;

FIG. 3 is a right side elevational view thereof;

FIG. 4 is a front elevational view thereof; and,

FIG. 5 is a rear elevational view thereof.

The broken line showing a shoe upper in the views, illustrates the portion of the design that forms no part of the claim. The broken line showing an elliptical shape on the arch, represents the boundary of the design, with the area within, forming no part of the claim. Neither of the broken lines forms any part of the claim.
